CLAIM

The ornamental design for a front panel for digital communications peripherals, as shown and described.

DESCRIPTION

FIG. 1 is a top front and right side perspective view of a front panel for digital communications peripherals showing our new design, the housing being shown in broken lines for illustrative purposes only and forms no part of the claimed design;

FIG. 2 is a left side elevational view thereof; and,

FIG. 3 is a bottom plan view thereof.

FIG. 1

FIG. 2

FIG. 3
